UNITED STATES PATENT OFFICE

99,317

DESIGN FOR A DRAWER PULL OR SIMILAR ARTICLE

Otto E. Uhlmann, Grand Rapids, Mich., assignor
to Keeler Brass Company, Grand Rapids, Mich.

Application December 30, 1935, Serial No. 60,334

Term of patent 3½ years

To all whom it may concern:

Be it known that I, Otto E. Uhlmann, a citizen
of the United States, residing at the city of Grand
Rapids, in the county of Kent and State of Michigan,
have invented a new, original, and ornamental
Design for a Drawer Pull or Similar Article,
of which the following is a specification, reference
being had to the accompanying drawing, forming
a part thereof.

Fig. 1 is a front view of a drawer pull, showing
my new design;

Fig. 2 is a side view thereof; and
Fig. 3 is an end elevational view.

I claim:

The ornamental design for a drawer pull or
similar article as shown.

OTTO E. UHLMANN.
